(57) **CLAIM**

The ornamental design for an electric coil fence assembly, as shown and described.

DESCRIPTION

FIG. 1 is a perspective view of an electric coil fence assembly showing my new design;

FIG. 2 is a side view thereof, the opposing side being identical to this view;

FIG. 3 is an end view of the electric coil fence assembly shown in FIG. 1, the opposing end being identical; and, FIG. 4 is an enlarged view of an insulator shown in FIG. 2. The broken lines in FIGS. 1 and 2 depict the bounds of the Claim that form no part of the claimed design.

The broken lines shown by the rectangle depicted as IV in FIG. 2 depict the limits of the enlarged area that forms no part of the claimed design.
